to Hampden Specialty Products, Inc., Easthampton, Mass., a corporation of Massachusetts

Application December 19, 1939, Serial No. 89,018

Term of patent 3½ years

To all whom it may concern:

Be it known that I, Edward A. Schaffer, a citizen of the United States, residing at Springfield, in the county of Hampden, and State of Massachusetts, have invented a new, original, and ornamental Design for a Magazine Rack or the like, of which the following is a specification, reference being had to the accompanying drawing, forming part thereof.

The figure is a perspective view of a magazine rack showing my new design.

I claim:

The ornamental design for a magazine rack, or the like, as shown.

EDWARD A. SCHAFFER.
